(57) **CLAIM**

The ornamental design for a portable data terminal, as shown and described.

DESCRIPTION

FIG. 1 is a perspective view of a portable data terminal;
FIG. 2 is a side of the portable data terminal shown in FIG. 1;
FIG. 3 is another side view of the portable data terminal shown in FIG. 1;
FIG. 4 is a front view of the portable data terminal shown in FIG. 1;
FIG. 5 is rear view of the portable data terminal shown in FIG. 1;
FIG. 6 is a top view of the portable data terminal shown in FIG. 1; and,
FIG. 7 is a bottom view of the portable data terminal shown in FIG. 1.

The portions shown in broken line are for illustrative purposes only and form no part of the claimed design.
